PORTABLE GAS STOVE CASE

Floyd O. Gruver, Jr., and William J. Marsh, Wichita, Kans., assignors to The Coleman Company, Inc., Wichita, Kans., a corporation of Kansas

Filed Oct. 9, 1968, Ser. No. 13,911

Term of patent 14 years

Int. Cl. D7—04; D3—01
U.S. Cl. D81—10

FIG. 1

FIG. 2

FIG. 3

FIG. 4

FIG. 5

FIG. 1 is a front elevational view of a portable gas stove case embodying our new design;

FIG. 2 is a rear elevational view;

FIG. 3 is a top plan view;

FIG. 4 is a bottom view, and

FIG. 5 is an end elevational view, taken from the left of FIG. 1, both ends being identical.

We claim:

The ornamental design for a portable gas stove case, as shown and described.
